CLAIM

The ornamental design for a machine for stringing racquets, substantially as shown and described.

DESCRIPTION

FIG. 1 is a side elevational view of a machine for stringing racquets showing our new design;

FIG. 2 is a side elevational view showing the side opposite that shown in FIG. 1;

FIG. 3 is a rear elevational view thereof;

FIG. 4 is a front elevational view thereof;

FIG. 5 is a top plan view thereof.

*Fig. 1.**Fig. 2.**Fig. 3.**Fig. 4.**Fig. 5.*
